UNITED STATES PATENT OFFICE.

CHARLES SCHMIDT, OF WEST MILWAUKEE, WISCONSIN.

OIL-CAN.

1,181,261.

Specification of Letters Patent.

Patented May 2, 1916.

Application filed March 18, 1914. Serial No. 825,464.

To all whom it may concern:

Be it known that I, CHARLES SCHMIDT, a citizen of the United States, residing at West Milwaukee, county of Milwaukee, and 5 State of Wisconsin, have invented new and useful Improvements in Oil-Cans, of which the following is a specification.

My invention relates to improvements in oil cans.

10 The object of my invention is to provide convenient and safe means for momentarily illuminating an oil cup or duct and also the nozzle of the oil can while adjusting said nozzle to the oil cup or duct.

15 In the drawings—Figure 1 is a side elevation, partly in vertical section, of an oil can embodying my invention. Fig. 2 is a rear elevation of the same. Fig. 3 is a detail view, in elevation, of the lower portion 20 of the can, showing the door to the auxiliary compartment.

Like parts are identified by the same reference characters throughout the several views.

25 The oil can A is provided with a spout B terminating in a nozzle b, through which the oil is delivered to an oil cup or to the part or bearing to be lubricated. The spout B has screw threaded connection with the 30 can and is provided with a knurled collar C to facilitate unscrewing it. All of these parts may be of any ordinary construction, except that the can A is provided with an auxiliary chamber E adapted to receive an 35 electric battery F, one pole of which is connected at a with the wall of the can and the other pole of which is connected at c, d, with the insulated terminal of a conductor e, f, h, leading to the lamp H. The sec- 40 tions e, f, of the conductor are normally electrically disconnected or are adapted to be connected up by a push button J, preferably mounted upon the handle D of the oil can in a position convenient for operation 45 by the finger or thumb of the same hand which supports and manipulates the oil can. The sections f, h, of the conductor above described are detachably connected by a slip coupling I, whereby the outer section h, to- 50 gether with the lamp, may be readily de-

tached and removed with the spout B, when the latter is unscrewed, or more specifically the sections may be uncoupled at I, preparatory to unscrewing the spout B. The conductor h is inclosed in an insulating sheath 55 K, which is clamped to the spout by clamping members L of any ordinary type. This sheath may have sufficient rigidity to support the lamp H in the most available position for illuminating the nozzle b, thus 60 avoiding the necessity of employing an additional clamp to support the lamp socket directly from the spout. The sheath K may also have sufficient flexibility to allow the lamp to be moved as may be necessary from 65 time to time to suit the requirements of different machinery. The battery F may be removed, renewed or replaced from time to time by opening a door G to the compartment E. This door is preferably hinged at 70 75 g³, and is normally secured in closed position by a sliding latch g, which is forked and is adapted to engage a catch pin g''. The particular style of door, door latch and catch is however not material and it will of course be understood that the arrangement of the conductor f upon the handle D is merely one of convenience, the object being to locate the push button at a convenient point for operation. 80

In use, the oil can is manipulated in the usual manner to bring the nozzle into proximity to the bearing or cup to which oil is to be delivered, and if the light is insufficient, the operator presses the button J, 85 whereupon the lamp will be lighted, thus enabling the operator to properly adjust the nozzle with accuracy and without delay.

I claim—

The combination of an oil can provided with a curved pouring spout and having a handle at the opposite side of the can from that toward which the spout is curved, an independent chamber formed on the base 95 of said can, an electric battery located in said base, an electric lamp mounted upon the pouring spout and supported within the arc of curvature thereof and near its extremity, and connected with the battery, and 100

a push button mounted upon the handle and controlling the circuit of said lamp, said pouring spout being detachable and said electrical connections between the battery and lamp being detachably coupled adjacent to the connection between the spout and the can.

In testimony whereof I affix my signature in the presence of two witnesses.

CHARLES SCHMIDT.
